MACHINE FOR PRESSING PULP ARTICLES

Merle P. Chaplin, Portland, Maine, assignor to
Chaplin Corporation, South Portland, Maine,
a corporation of Maine

Application October 18, 1949, Serial No. 122,001

4 Claims. (Cl. 92—59)

1

This invention relates to apparatus for making molded pulp articles wherein a formed pulp article is adapted to be compressed between dies for the purpose of compacting the article. In some of such apparatus, one or both of the dies which contact opposite surfaces of the article, is heated to dry and finish the article under conditions of heat and compression. Examples of this general type of apparatus are found in my prior Patent No. 2,388,828, issued November 13, 1945, as well as in my pending application Ser. No. 708,661, filed November 8, 1946, and in the patent of Harbrecht No. 1,377,342, dated May 10, 1921.

In all of these prior structures, the formed article is compressed between upper and lower dies of mating die couples which are separated to permit the formation or placement of the formed article on one die of each of the couples and the dies of said couples are then brought into mating relation to effect compression of the thus formed article. The compression thus applied in many instances is relatively high, the dies being forced toward one another against the interposed article under great pressure. Consequently apparatus of this character has heretofore been made heavy and cumbersome in order to withstand the pressures thus mechanically exerted.

In most apparatus of this type, the movement of the dies through the orbit or path of their travel is not continuous but intermittent, the apparatus being operated through step-by-step movement with intervening periods of rest or dwell. When the moving parts are made heavy and bulky, their inertia causes serious problems in intermittent operation and it is therefore highly desirable, not only from a mechanical standpoint but from the standpoint of operation as well, to make the moving parts of such apparatus as light as possible and yet strong enough to stand the pressures to which I have referred. The present invention permits this to be done.

In the machine of my prior Patent No. 2,388,828, the article is formed on appropriate suction forming dies and subsequently transferred to drying dies. These drying dies are arranged in couples, each couple embodying an upper and lower die. The dies of the several couples are mounted to bodily rotate through an orbit about a fixed vertical axis. Through a portion of their angular rotation they are separated to permit the formed article to be transferred from the forming dies to one of the lower drying dies. Through the remainder of the angular rotation

of the drying dies, said drying dies are brought into mating relation to compress and dry the article and they are then separated again to permit of the removal of the finished article. 5 The placing of the article under compression between these drying dies is accomplished by a cam track which progressively brings the dies into mating relation until the desired predetermined pressure is obtained and the cam track 10 then permits gradual separation of the dies until they are finally fully separated to remove the article. During a portion of this drying cycle there is a steady build-up of pressure to the maximum pressure and thereafter a steady decrease 15 in pressure, with a maximum pressure present through a relatively small angular movement of the drying dies. It is at this point of maximum pressure that the greatest strength is required in the machine to withstand the high pressures 20 thus impressed upon the article. For the rest of the drying cycle relatively less strength of the parts is required.

In adapting the invention to the machine of my said prior patent, I position at this point of 25 maximum pressure a hold down device mounted in stationary position exterior of the path of travel of the dies and having anti-friction coaction with the carrier of the upper drying dies, so as to permit said dies to readily rotate through 30 their orbit but to form a strong pressure resistant abutment against upward yielding of said dies during the application of maximum pressure thereto. The hold down device is rigid with the base or foundation of the machine so that the 35 upward pressure of the lower dies will react against said base or foundation. Thus the upper and lower dies are tied together through the foundation of the machine and through the hold down device through that angular portion of the 40 travel of the dies where the pressure is the greatest.

In practice a plurality of such hold down devices may be employed but I find that, in a machine according to my said patent, a single hold 45 down device will permit me to make the operating parts of the machine many hundreds of pounds lighter than would otherwise be the case if the former practice (devoid of the present invention) were employed. By thus minimizing the weight 50 of the operating parts, the initial cost of the machine is materially reduced, the machine may be operated with much less power than otherwise, and the operation is much smoother than with a heavy machine. Furthermore, since the inertia

of the parts is reduced to a minimum, wear is minimized and considerably less maintenance is required.

Features of the invention other than those specified will be apparent from the following detailed description when read in conjunction with the accompanying drawings.

In said drawings:

Fig. 1 is a fragmental radial section through a machine embodying the present invention.

Fig. 2 is a fragmental plan view taken from the plane of the line 2-2 of Fig. 1.

Fig. 3 is a section on the line 3-3 of Fig. 1.

Fig. 4 is an elevation of the hold down device of this invention looking from the left hand side of Fig. 1.

Fig. 5 is a section on the line 5-5 of Fig. 2.

Fig. 6 is a section on the line 6-6 of Fig. 2.

For the purpose of illustrative disclosure of the present invention, I have chosen to show the same in the accompanying drawings as incorporated in a machine such as illustrated in my prior Patent No. 2,388,829, and I have shown in the accompanying drawings only so much of the machine as will make the adaptation of the invention thereto clear and explicit. In the following detailed description the reference characters used will, so far as is practical, be the same as those found in my said patent for corresponding parts of the machine.

The machine of the accompanying drawings is provided with a base 20 mounted upon and riveted, welded or otherwise firmly secured to a structural steel platform 301 which constitutes a firm foundation for the whole structure. On said base is supported a hollow vertical shaft 100. On the lower portion of this shaft is mounted a plurality of lower radial arms 102, corresponding in number to the number of drying die couples in the machine and forming a carrier for the lower dies. To the upper portion of the shaft 100 are rigidly affixed a corresponding number of upper radial arms 103 forming a carrier for the upper dies. To the under side of each of these upper arms and near its outer end is secured a heater plate 81 and to the under side of which is fixed an upper drying die 80. A corresponding lower mating die 90 is mounted on a heater plate 91 which is in turn supported on a co-axial spindle 105. This spindle is mounted for vertical reciprocation in a spindle bearing 102a carried by and rigid with the subjacent lower arm 102. Below said bearing the spindle is provided at its lower end with rollers 107 which run over an arcuate cam track 108, supported on compression springs 114 which may be adjusted to regulate the amount of pressure placed on the article between the upper and lower dies during various stages of drying.

Embracing the outer ends of the lower radial arms 102 is an annular gear 86 extending entirely around the machine and this gear is intermittently driven through connections such as described in my said prior patent, to rotate the arms 102 and 103 and the shaft 100 about the axis of said shaft in an intermittent manner, with intervening periods of dwell to permit of the transfer of formed articles to the drying dies and their subsequent removal from said dies in finished condition—all as fully described in my said prior patent.

During rest periods between bodily rotation of the dies, articles are placed on the lower drying dies, while the latter are in lowered position, are raised into contact with the corresponding upper

mating dies and then progressively compressed for a portion of the rotary cycle. During this interval the pressure is built up as the dies are progressively moved until compression reaches the maximum. Thereafter progressive movements of the dies are accompanied by a progressive decrease in pressure. At the point of substantially maximum compression in the circumferential movement of the dies, the hold down device of the present invention is positioned. It embodies the structure next to be described.

Mounted on a structural platform 301 which supports the base 20 is a structural steel footing 302, all parts of which are welded together and to the platform so as to form a rigid anchorage for the hold down device. To this footing is firmly bolted or welded a base plate 303 on which are superimposed two upright columns 304, arranged in vertical, spaced apart relation and connected to one another by gusset plates or webs 305 welded to both columns. A top plate 306 is secured to the upper end of these columns by welding or otherwise.

Inasmuch as the columns are spaced apart in a direction radially of the shaft 100 they will constitute a rigid assembly effectually braced in this radial direction. They are braced against deflection in a direction circumferential of the machine by means of tie rods 307 which pass through a yoke 308 welded to one of said columns and anchored at their lower ends to the footing 302, as shown best in Fig. 4. The columns 304 are thus firmly braced in all directions against lateral deflection.

Resting upon the upper surface of the top plate 306 is a cap plate 309. This cap plate carries a bracket 310 positioned midway between the lateral edges of the plate and extending to overlie the upper portions of the outer ends of the upper arms 103. The free end of this bracket carries an upright stub shaft 311 and this shaft in turn carries a tie roller 312 supported on the stub shaft with interposed anti-friction bearings 313, as shown best in Fig. 6. The roller 312 is thus free to rotate while in engagement with the inner periphery of a track 314. This track is of annular form. It extends entirely around the machine and is superimposed upon a reinforcing ring 315 welded to the top of the upper arms 103, i. e. to the carrier of the upper dies, as best shown in Fig. 1. The track 314 and ring 315 form a rigid construction against which the roller 312 may engage to radially tie together the hold down device and the rotary parts of the drying unit of the machine. The track and ring are reinforced in a vertical direction by an annular skirt plate 316 which embraces the outer end of the several arms 103.

Mounted on the opposite sides of the bracket 310 on the cap plate 309 are a pair of fittings 317 each of which supports a horizontal stub shaft 318 shown best in Fig. 5. Each of these stub shafts projects inwardly over the track 314 and carries a roller 319 with interposed anti-friction bearings 320. These two rollers 319 both engage with and are adapted to ride upon the upper surface of the track 314 and function as hold down rollers to withstand upward yielding of the arms 103 under the upward pressure imparted by the lower dies 80.

The rollers 312 radially tie together the hold down device and the drying unit while the rollers 319 hold down the upper dies 80 so that they cannot yield to upward pressure during that portion of the rotary cycle of operation where such

pressure is at its maximum. In the machine with which the present invention is shown as associated, a single hold down device positioned as stated will thoroughly safeguard the parts against breakage or undesirable flexion or yielding and permit the die supporting parts of the drier unit to be made relatively light for the reasons hereinbefore described. Two or more of such hold down units may be desirable in some machines, the same being spaced apart about the path of travel of the dies as circumstances may require but a single hold down device is sufficient in the machine described.

The foregoing detailed description sets forth the invention in its preferred practical form, but the invention is to be understood as fully commensurate with the appended claims.

Having thus fully described my invention, what I claim as new and desire to secure by Letters Patent is:

1. In a machine for making pulp articles wherein a plurality of die couples each composed of upper and lower mating dies are carried by upper and lower carriers supported on a vertical shaft mounted on a firm foundation to travel through an endless orbit with each of the lower dies of said couples progressively applying to an interposed pulp article pressure which increases to a predetermined maximum for a portion of the travel of said dies through said orbit and thereafter progressively decreases during a further portion of such travel, the improvement which comprises: an endless annular track common to all of the upper dies mounted at a fixed horizontal elevation on and coaxially rotatable with the carrier of said upper dies, a single hold-down device rigidly anchored to the foundation and upstanding exteriorly of and contiguous to said orbit at the zone of maximum pressure of

5

said die couples in said orbit, a hold-down roller carried by the hold-down device and non-yieldably engaging the upper surface of said track during the passage of progressive portions of such track through said zone of maximum pressure, and a tie roller also carried by the hold-down device and engaging with the inner periphery of said track.

2. A machine as claimed in claim 1, wherein there are a plurality of hold-down rollers engaging the upper surface of said track, and an additional tie roller acting against the inner periphery of said track in said opening of maximum pressure.

3. A machine as claimed in claim 1, wherein there are two hold-down rollers engaging the upper surface of said track, and a single interposed tie roller acting upon the inner periphery of the track in said zone of maximum pressure.

20 4. A machine as claimed in claim 1, wherein the hold-down device embodies a plurality of upright columns laterally spaced from one another and braced against deflection both radially and tangentially of the machine.

25

30

35

said die couples in said orbit, a hold-down roller carried by the hold-down device and non-yieldably engaging the upper surface of said track during the passage of progressive portions of such track through said zone of maximum pressure, and a tie roller also carried by the hold-down device and engaging with the inner periphery of said track.

2. A machine as claimed in claim 1, wherein there are a plurality of hold-down rollers engaging the upper surface of said track, and an additional tie roller acting against the inner periphery of said track in said opening of maximum pressure.

3. A machine as claimed in claim 1, wherein there are two hold-down rollers engaging the upper surface of said track, and a single interposed tie roller acting upon the inner periphery of the track in said zone of maximum pressure.

4. A machine as claimed in claim 1, wherein the hold-down device embodies a plurality of upright columns laterally spaced from one another and braced against deflection both radially and tangentially of the machine.

MERLE P. CHAPLIN.
